UNITED STATES PATENT OFFICE.

WILLIAM A. TROY, OF ARCHBALD, PENNSYLVANIA.

AUTOMATIC REGISTER.

1,297,752.

Specification of Letters Patent. Patented Mar. 18, 1919.

Application filed May 22, 1918. Serial No. 235,958.

To all whom it may concern:

Be it known that I, WILLIAM A. TROY, a citizen of the United States of America, and resident of Archbald, in the county of Lackawanna, in the State of Pennsylvania, have invented new and useful Improvements in Automatic Registers, of which the following, taken in connection with the accompanying drawings, is a full, clear, and exact description.

This invention relates to a certain new and useful automatic register for vehicles, such as street cars, motor buses, and the like.

The primary object of the invention is to provide a register for the purpose described, in which each person in getting into the vehicle operates the register mechanism to indicate his presence as a passenger.

A further object is to provide a device of the class identified of relatively simple construction, and which is efficient in operation and returns itself to starting position after each operation at a rate sufficiently rapid to prevent entry of any person to the vehicle without operating the registering mechanism.

Other objects and advantages relate to the details of construction and operation, as will more fully appear from the following description, taken in connection with the accompanying drawings,—in which

Figure 1 is an elevation, partly in section, of an apparatus constructed in accordance with my invention.

Fig. 2 is an elevation of the portion of the mechanism which preferably may be located beneath the floor of the vehicle.

Fig. 3 is a perspective view of the cam or dog forming a portion of the operating mechanism.

The device, as shown, embodies a step which may be divided into any number of parts and is indicated in Fig. 2 as formed of three sections —1—, —2— and —3—, each 45 pivotally carried by the vehicle body through the medium of brackets —4— to which the step sections may be independently pivoted.

Preferably beneath the floor of the vehicle body and adjacent the step sections carried thereby are mounted a series of plungers —5— equal in number to the number of step sections.

The lower end of these pistons is adapted to rest upon the inner end of its respective 55 step section and is held in such position by coil spring —6— mounted on the piston

within a casing —7— and having its upper end bearing against the casing and its lower end in contact with a collar —8— rigidly secured to the plunger.

The casings —7— may, as shown, be secured to the rear of the vertical portion —9— of the vehicle body.

The upper end of the plunger —5— is secured to one end of a bell-crank lever —10—, 65 the opposite end of the bell-crank lever being secured to a thrust-bar —11—.

The connection between the plunger —5— and bell-crank —10— may be of a loose or slotted character to permit vertical movement of the plunger, and thereby effect rotary movement of the bell-crank, and the mounting for the bell-crank may be carried in any suitable manner by the vehicle body, and is shown in the form of a bracket —12— 75 secured to the under side of the vehicle body.

The thrust-bar —11— is provided with a slot —12'— through which one end of a spring bar —13'— extends, the extending end of said bar being secured to the bell-crank —10 and its opposite end lying in contact with the thrust-bar —11— and normally tending to rotate the thrust-bar about its pivot on the bell-crank —10— in a downward direction for a purpose hereinafter 85 described.

The thrust-bar —11— normally lies in a recess —18— formed in a cam —14— so that vertical movement of piston —5— effecting a rotary movement of bell-crank —10— and 90 substantially horizontal movement of the thrust-bar —11— effects a rotary movement of the cam —14— to elevate the rod —15—, eccentrically secured to the shaft —16— by crank arm —17—, it being understood that 95 cam —14— is rigidly mounted upon the shaft —16—, such shaft being carried by a series of brackets —18— secured to the under side of the vehicle body.

Vertical movement of the rod —15— in 100 turn effects a rotary movement of the bell-crank —19—, to one arm of which the rod is pivotally secured. The opposite arm of the bell-crank is in turn pivotally secured to a bar —20— operatively engaged with the operating portion —21— of any suitable and well-known counting or registering device —A—.

The bell-crank —19— may be rotatably supported in any suitable manner, as upon a 110 shaft —22— carried by the vehicle.

The cam —14— is provided with a radial

projection —23— adapted to move the thrust-bar —11— from recess —13— when the cam has been rotated by the thrust-bar so as to move the projection —23— a sufficient distance to elevate the thrust bar —11— above the exterior surface of the portion of the cam about the recess —13—.

When the thrust bar —11— has been so elevated in the operation of the apparatus, a spring —24— is provided for returning the cam to normal starting position, and this spring may, as shown, be operatively secured to the vehicle body and the cam in any suitable manner, as by the screw shown. When the cam has been returned to normal starting position, the piston and the bell-crank and thrust-bar operatively associated therewith are likewise immediately returned to starting position when the weight of the person is removed from the step section, as —1—, —2— or —3—. This return is automatically effected by spring —6—.

As indicated, a distinct operating mechanism is provided for each step section, such operating mechanism including a piston and its inclosing easing and associated spring, a bell-crank —10—, a thrust-bar —11— and a suitable cam —14—.

These bell-cranks —10— are preferably mounted upon a single shaft —25—, carried by brackets —12— and the cams —14— are preferably carried by a single shaft —16—, as heretofore described, so that operation of any one of the step sections effects a rotation of shaft —16—, which shaft actuates the rod —15— through the medium of crank arm —17—.

If a single step is used, it will be understood that the projection —23— may be omitted from the dog —14—, the particular use for which this projection is designed being to permit successive operation of the register mechanism by a series of step sections, even if there is only a fraction of a second difference between the time that the different persons tilt the different step sections by stepping thereon.

The extent of tilting movement of the step section may be regulated and adjusted to effect the desired and necessary movement of the piston —5— to properly actuate the register mechanism.

Although I have shown and described a specific construction, form and relation of parts as illustrative of my invention and as perhaps exemplifying a preferred embodiment thereof, it should be understood that I

do not desire to limit myself to any particular construction, form or relation of the parts, except as hereinafter specifically set forth in the claims, as various modifications and changes may be made in each of the same without departing from the spirit of this invention as set forth in the claims here- to appended.

What I claim is:

1. In an apparatus of the class described, a movable part, a plunger operated thereby, a bell crank operated by the piston, a thrust-bar actuated by the bell crank, a cam adapted to be rotated by movement of the thrust-bar in one direction, a registering mechanism, means actuated by the cam for operating the registering mechanism, means for returning the thrust-bar and its operating parts to starting position independently of the cam and the mechanism actuated thereby, and additional means for returning the cam to starting position after each actuation by the thrust-bar and independently of the thrust-bar movement.

2. In an apparatus of the class described, a plurality of movable step sections, a shaft, a plurality of cams mounted on said shaft and corresponding in number with said step sections, means actuated by respective step sections for actuating the corresponding cam to rotate said shaft, a counting mechanism, means actuated by the rotation of said shaft for operating the counting mechanism and means for returning the said shaft to normal starting position after each actuation independently of the particular mechanism that effected the actuation.

3. In an apparatus of the class described, a plurality of movable step sections, a shaft, a plurality of cams mounted on said shaft and corresponding in number with said step sections, means actuated by respective step sections for actuating the corresponding cam to rotate said shaft, a counting mechanism, means actuated by the rotation of said shaft for operating the counting mechanism, means for removing the actuating mechanism out of the path of movement of the actuated ratchet to permit said shaft to return to normal starting position independently of the said mechanism.

In witness whereof I have hereunto set my hand this 16th day of May, 1918.

WILLIAM A. TROY.
